TAPPING MACHINE

George W. Emrick, Brooklyn, N. Y.

Application March 5, 1936, Serial No. 67,272

20 Claims. (Cl. 10—129)

This invention relates to machines designed to perform tapping operations in a workpiece; and the object of the invention is to provide a machine of the class described employing a foot-actuated lever or treadle for actuating the tapping attachment of the machine to move the same in the direction of the work or workpiece, and especially in the provision of a substantially balanced treadle weight to not only balance the tapping attachment and associated parts, but also sufficient to move said parts upwardly out of engagement with the workpiece after performing a tapping operation, and this structure further provides very light treadle operation which relieves the labor or fatigue in the manual operation of the machine to a large degree; a further object being to provide a resilient coupling between the foot lever and the operating rods coupled with the tapping attachment whereby movement is imparted to the attachment through said yieldable or resilient coupling; a further object being to provide a yielding buffer checking sudden upward movement of the lever when the foot is released therefrom; a further object being to provide adjustable means for checking the downward movement of the foot lever as well as independent adjustable means for limiting or gaging the downward movement of the tapping attachment including the tap supported thereby; a further object being to provide anti-frictional means for mounting, bracing and guiding the tapping attachment and associated parts in the standard of the machine; a further object being to provide means for relieving stresses or strains on the quill of the machine; a still further object being to provide a workpiece stripping device including an adjustable strip or plate, said device being adjustable on the frame of the machine and relatively to an adjustable bed plate or table; and with these and other objects in view, the invention consists in a machine of the class defined which is simple and economical in construction and which is constructed as more fully hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view of a machine made according to my invention with parts of the construction broken away; and, 55 Fig. 2 is a partial section on the line 2—2 of Fig. 1.

In carrying my invention into effect, I provide a base 5 consisting of a channeled base plate 6 having upwardly directed side brackets 7 terminating at their upper end in a split bearing 8

which may be clamped by means of a bolt indicated at 9 upon the lower end of a vertical column or standard 10 of the machine, the same being in the form of a tube in the construction shown. Secured upon the upper end of the column 10 is an operating or driving head 11 which includes the usual mechanism for actuating the spindle 12 which extends below the lower end of the quill 13. The head 11 is more or less of conventional construction such as employed in certain types of drill presses, and for this reason, the details of the head are not shown nor described as they formed no direct part of this invention, and any particular type of drive for the spindle 12 may be provided. 15

The head 11 in the construction shown has an electric motor 14 supported at one side thereof. On the shaft of the motor are a number of pulleys 15, around which a belt 16 passes, said belt passing around corresponding pulleys on the shaft 17, the pulleys being arranged in a hood or housing 18. This construction is to provide the conventional variable speed drive of the shaft 17. Clamped to the lower end portion of the quill 13 is an adapter 19, to the lower surface of which is detachably supported a tapping attachment 20 which may be of any described type and construction. In practice, the adapter 19 as well as the various attachments 20 employed may be so constructed as to have the adapter 30 constitute a universal mounting for different kinds and classes of tapping attachments. 25

At 21, I have shown a tap supported in connection with the attachment and projecting below the lower surface thereof. At 22, I have shown the bed plate or workpiece supporting table which is longitudinally and circumferentially adjustable upon the column 10 and clamped in different positions of adjustment by means of the hand screw lever 23. At 24, I have shown a stripping device which is also vertically and circumferentially adjustable upon the column 10 and has a clamping lever 25 similar to the lever 23 for securing the device in different positions of adjustment. A stripping plate or arm 26 is 40 adjustably mounted in connection with the device by means of screws 27 operating in an elongated aperture 28 in said device 24 to adjust the position of the plate 26 with respect to the tap 21 to compensate for workpieces of various kinds 45 and classes. 50

Mounted in one side of the adapter 19 and projecting upwardly at one side of the head 11 is a stop rod 29 which is threaded to receive adjusting nuts 30 which control and regulate, or, in other words, limit the downward movement of the attachment 20 or the tap 21 with respect to a suitable workpiece. The rod 29 is guided in the head 11 by passing through suitable bearings 31 projecting outwardly from the head 11. Cou- 60

pled with the upper end of the rod 29 is a torsion spring 32 which is also secured to the head 11 as indicated at 33. This spring serves to eliminate or take up the torsional stresses or strains to which the quill 13 may be subjected in the operation of the machine. In this connection, it will be understood that the head 11 is modified in its construction to a slight degree in adapting the same for use as a tapping machine, and in lieu of this modification, the desirability of employing the torsional spring 32 is regarded as practical.

Mounted in the side brackets or plates 7 of the base 5 at the rear portion thereof is a shaft 34 on which is preferably arranged a ball bearing 35 to provide an anti-frictional pivot mounting of the treadle or lever 36 which extends forwardly between the plate 7 and terminates at its free end in a foot piece 37. The lever 36 is angular in form and includes a rearwardly extending arm 38 upon which is mounted an upwardly extending rod 39 for retaining a plurality of ring-like weights 40 upon the upper surface of the arm 38. The arm 38 of the lever 36 is provided with an upwardly directed stop surface 41, near the pivot 34.

Freely extending through the arm 38 is a rod 42 supported in connection with the base plate 6 as seen, and the upper end of which is threaded to receive a milled stop adjusting nut 43 and a wing-like nut 44. The lever 36 adjacent the pivot 34 is provided with an angularly extending seat 45 in connection with which a buffer rod 46 is adapted to operate in checking or cushioning the upward movement of the lever 36 in the sudden removal of the foot therefrom. The rod 46 is mounted in a sleeve 47 adjustably mounted in the head 8 in an angular position substantially as shown in the drawing. A set screw 48 is employed to retain the sleeve 47 in different positions of adjustment.

The rod 46 constitutes a plunger which is adapted to operate upon a coil spring 49 arranged in the sleeve 47 and around a guide rod or bolt 50 which is coupled with the upper end of the plunger 46 and extends through the outer end of the sleeve. The rod 50 has a nut or head 51 which limits the downward movement of the plunger 46. Mounted in the central or corner portion of the lever 36 is a transverse pin or bolt 52 which forms a pivot for the lower end of an eye-bolt 53. A sleeve nut 54 is adjustably mounted on the bolt 53 and serves to raise and lower the position of the plunger tube 55 on the eye-bolt 53. Said bolt extends into the plunger tube 55 to provide a bearing and guide therefor, but said tube is movable longitudinally of said bolt.

A nut 56 is adjustably mounted on the sleeve nut 54 and secured to this nut is a coil spring 57, the upper end of which engages a swivel 58 which seats upon a collar 59 secured to the tube 55. The spring 57 operates to normally support the tube 55 upon the upper surface of the sleeve nut 54. The plunger 55 extends upwardly through the column 10, and an eye-bolt or pin 60 is secured in the upper end thereof, to which is pivoted the lower yoke-shaped end of a plunger body 61 as seen at 62. Rotatably mounted on the upper and lower end portions of the body 61 are pairs of guide and bearing wheels 63 which serve to freely or anti-frictionally guide and brace the body 61 in its movement longitudinally of the column 10.

Centrally of the body 61 is an enlargement 64

to which is secured a rod 65 which passes outwardly through an elongated opening 66 formed in the column 10. The free end 67 of the rod 65 is supported in the adapter 19 as clearly seen. A supplemental plunger 68 may be coupled with the upper end of the body 61 as indicated in dotted lines in Fig. 1, and this plunger extends upwardly beyond the head 11 and is provided with a seat 69 upon which supplemental counter-balance weights 70 may be supported, if desired. The parts 68, 69 and 70 are indicated in dotted lines, solely for the reason that they are not an essential part of the machine and may or may not be employed.

The adjustment of the sleeve nut 54 will control and regulate the position of the quill 13 and tapping attachment 20 with respect to the head 11, that is to say, the position to be assumed by said parts when at the upper end of the stroke. This adjustment will also regulate the height of the treadle or foot lever 36 to suit the operator. After this adjustment has been arranged to suit the operator and the work upon which the tapping is to be performed, and after other adjustment of the bed plate 22 and stripping device 24 is made, the buffer plunger 46 or its supporting sleeve 47 will be adjusted so as to provide the desired buffer action against the treadle when released to check the upward movement of the tapping attachment 20 by the spring 57 and weights 40. As long as the same tapping attachment is employed with a tap 21 of substantially the same size and weight, no further adjustment need be made with respect to the treadle and parts above referred to, especially when tapping the same general class of work. The weights 40 may be changed to compensate for any change made in the machine, without changing the treadle or lever adjustment. With different work-pieces, the table 22 and stripping device 24 alone may be adjusted without interfering with the treadle or foot lever and tapping attachment adjustment.

In the upward movement of the attachment out of engagement with a workpiece, the weights 40 act through the lever 36, the bolt 53 and the sleeve nut 54 to positively engage the lower end of the tube 55 in performing this operation.

With different workpieces, the nuts 39 will be adjusted to gage the downward movement of the tap 21 into the workpiece, and when this adjustment is made, the nut 43 is adjusted to effect a stop of the lever 36 at a point slightly beyond that of the adjustment of the nuts 39 so that the lever has a slight travel beyond the travel necessary to bring the nut 39 into engagement with the bearing guides 31 which also function as stops limiting the downward movement of the rod 29. It is understood in this connection, that the independent movement of the lever is possible through the spring 57. The nut 43 operates to check any unnecessary strain or stress on the spring 57.

After the various adjustments and balancing of the machine have been made, the machine is ready for operation. The switch 14a of the motor 14 may be moved to put the motor into operation, which, in turn, will cause the tool 21 to be operated through the attachment 20 and the driven spindle 12 which is coupled with the attachment or the drive mechanism of the attachment as in other devices of this kind. The workpiece is now placed upon the bed plate or table 22, and the operator depresses the treadle or foot lever 36, in which operation, the plunger

body 61 carrying the attachment 20 and associated parts is moved downwardly, the plunger tube 55 being drawn downwardly through the spring 57 which forms a yielding or resilient coupling between the eye bolt 53 and the plunger tube 55, thus eliminating a positive mechanical movement of the tap 21 into the work, but on the other hand, provides a yieldable feed of the tap into the work. The weight of the tapping attachment and associated parts including the weight 70 if employed, will aid in the downward movement of the tap the instant that slight pressure is applied to the treadle, and this movement is against the action of the counterbalance weights 40. When the tap 21 reaches the limit of its downward stroke, which is gaged by the stop nuts 30, the treadle 36 will be released and the extended spring 57 will contract to bring the upper end of the sleeve nut 54 into engagement with the plunger tube 55, and the balance weights 40 will operate to move the tap 21, attachment 20 and associated parts upwardly, and this upward movement is checked by the buffer rod or plunger 46.

At this time, it is well to bear in mind that the tapping attachment 20 has a reverse drive as in devices of this kind commonly known, which feeds the tap out of the workpiece, and a strip or plate may be utilized by the operator, if desired, especially in tapping relatively light work, to support the work against the action of the tapper in its upward movement. Sufficient clearance will be provided at all times between the adapter 19 and head 11 to provide for a movement of the tap 21 out of engagement with the workpiece when supported on the stripper device as well as to compensate for the upward travel of the plunger beyond a point of normal balance.

In the above described operation of releasing the pressure on the treadle 36 to permit upward movement of the attachment 20 including the tap 21, this operation may be performed by sudden removal of the foot from the treadle, or in other cases, by simply raising the foot to gradually release the pressure on the treadle. The mode of this operation will be gaged and regulated by the operator of the machine to care for the tapping of workpieces of various kinds and classes.

A machine of the character described is simple and economical in construction, as well as neat and finished in its appearance; and by arranging the plunger rod 55 and its associated parts within a tubular column or within the boundaries of a standard, no interference is made to the rotatable as well as longitudinal adjustment of the bed plate and stripping device. At the same time, protection is afforded to the plunger tube, plunger body and associated parts that are disposed within the standard or column 10.

Furthermore, a machine of the character defined will speed up the tapping of workpieces and will perform the desired tapping operations in a substantially fool-proof manner, which will effect a saving in the breakage or destruction of taps as commonly experienced, especially by reason of the fact that the tap is moved or fed into the workpiece through a yielding or resilient coupling which will not permit the forcing or jamming of the tap into the workpiece.

Having fully described my invention, what I claim as new and desire to secure by Letters Patent, is:

1. A machine of the class described comprising a base, a standard, a tool operating attachment, means at the upper end portion of the standard

for supporting, guiding and operating said attachment to rotate a tool supported therein, and manually operated means including a yielding coupling and a plunger arranged longitudinally of said standard for moving said attachment and the tool supported therein in the direction of a workpiece supported in the machine, and means in operative engagement with said last named means for counterbalancing the weight of said attachment and associated parts to move the attachment away from the work when said manually actuated means is released.

2. In a tapping machine employing a tool operating head, a tapping attachment movable with respect to said head, means at one side of and in spaced relation to said attachment for supporting and guiding the attachment in its movement relatively to said head and toward and from a workpiece in performing a tapping operation, and said means involving a plunger having spaced anti-frictional means for supporting and guiding the plunger in its movement with respect to a support on the machine.

3. In a machine of the class described employing a tapping attachment movable toward and from a workpiece, manually actuated means including counterbalancing means for operating said attachment whereby in each cycle of operation the attachment moves by gravity into engagement with the workpiece and is fed into the workpiece through the added action of a yieldable coupling to eliminate stress or strain on the tool in performing a tapping operation and further whereby, in the reverse movement of the attachment, the tool thereof is positively moved out of the workpiece by the aid of said counterbalancing means.

4. In a tapping machine employing a tapping attachment movable toward and from a workpiece supported in the machine, means for controlling the movement of the attachment toward and from a workpiece comprising a treadle pivotally supported in the machine and in operative engagement with said attachment, means on the treadle for counterbalancing said attachment and associated parts to move the attachment upwardly out of engagement with a workpiece when the treadle pressure is released, and a buffer in operative engagement with the treadle to check the action of said counterbalancing means and to substantially balance the same when the attachment is in normal position.

5. In a tapping machine employing a tapping attachment movable toward and from a workpiece supported in the machine, means for controlling the movement of the attachment toward and from a workpiece comprising a treadle pivotally supported in the machine and in operative engagement with said attachment, means on the treadle for counterbalancing said attachment and associated parts to move the attachment upwardly out of engagement with a workpiece when the treadle pressure is released, a buffer in operative engagement with the treadle to check the action of said counterbalancing means and to substantially balance the same when the attachment is in normal position, means for operating and guiding the attachment in its movement in the machine, and tensional means compensating for the torsional stresses to which the last named means is subjected in the operation of said attachment.

6. In a machine of the class described employing a tapping attachment with means for operating a tool supported in the attachment,

- means for moving the attachment toward and from a workpiece, said means involving a plunger and a treadle, said treadle having a yieldable coupling with the plunger to eliminate the stress 5 and strain on a tool in the operation of feeding the same into a workpiece, and said plunger including adjustable means for increasing or decreasing the length thereof.
7. In a tapping machine employing a tapping 10 attachment in connection with which a tap is supported, means for rotating said tap through the attachment, a workpiece support adjustable relatively to said attachment, means for supporting and guiding the attachment to permit movement thereof toward and from a workpiece, means for normally supporting the attachment in spaced relation to the workpiece, and manually actuated means involving a yielding coupling for moving the attachment and associated parts in 15 the direction of a workpiece to control the feed of the tool of said attachment into the workpiece in a tapping operation.
8. In a tapping machine employing a tapping 20 attachment in connection with which a tap is supported, means for rotating said tap through the attachment, a workpiece support adjustable relatively to said attachment, means for supporting and guiding the attachment to permit movement thereof toward and from a workpiece, means 25 for normally supporting the attachment in spaced relation to the workpiece, manually actuated means involving a yielding coupling for moving the attachment and associated parts in the direction of a workpiece to control the feed of the 30 tool of said attachment into the workpiece in a tapping operation, and adjustable means for gaging the movement of the attachment in the direction of the workpiece.
9. In a tapping machine employing a tapping 35 attachment in connection with which a tap is supported, means for rotating said tap through the attachment, a workpiece support adjustable relatively to said attachment, means for supporting and guiding the attachment to permit movement thereof toward and from a workpiece, means for normally supporting the attachment in spaced relation to the workpiece, manually 40 actuated means involving a yielding coupling for moving the attachment and associated parts in the direction of a workpiece to control the feed of the tool of said attachment into the workpiece in a tapping operation, adjustable means for gaging the movement of the attachment in the direction of the workpiece, and other adjustable 45 means for limiting the movement of said manually actuated means in the operation of feeding the attachment in the direction of a workpiece.
10. In a tapping machine employing a tapping 50 attachment in connection with which a tap is supported, means for rotating said tap through the attachment, a workpiece support adjustable relatively to said attachment, means for supporting and guiding the attachment to permit movement thereof toward and from a workpiece, means for normally supporting the attachment in spaced relation to the workpiece, manually 55 actuated means involving a yielding coupling for moving the attachment and associated parts in the direction of a workpiece to control the feed of the tool of said attachment into the workpiece in a tapping operation, adjustable means for gaging the movement of the attachment in the direction of the workpiece, other adjustable 60 means in the operation of feeding the attach-

ment in the direction of a workpiece, and said third named means serving to move the attachment away from the workpiece when said manually actuated means is released.

11. In a machine of the class described comprising a base, a tubular standard extending upwardly from the base, a tool operating head at the upper end of the standard, a tool operating attachment, a plunger mounted in said standard and having means therein and projecting therefrom for supporting and guiding the attachment in the movement of the attachment longitudinally of the standard and said head, a treadle pivotally mounted in the base of said machine, and means involving a yieldable coupling for placing 15 said plunger in operative engagement with the treadle whereby in the downward movement of said treadle, said attachment is fed downwardly through the action of said yieldable coupling.

12. A machine of the class described comprising a base, a tubular standard extending upwardly from the base, a tool operating attachment, a plunger mounted in said standard and having means therein and projecting therefrom for supporting and guiding the attachment in 20 the movement of the attachment longitudinally of the standard and said head, a treadle pivotally mounted in the base of said machine, means involving a yielding coupling for placing said plunger in operative engagement with the treadle 25 whereby in the downward movement of said treadle, said attachment is fed downwardly through the action of said yieldable coupling, and means in operative engagement with the treadle 30 for moving the attachment upwardly out of engagement with a workpiece when the downward pressure on said treadle is released.

13. A machine of the class described comprising a base, a tubular standard extending upwardly from the base, a tool operating head at the 40 upper end of the standard, a tool operating attachment, a plunger mounted in said standard and having means therein and projecting therefrom for supporting and guiding the attachment in the movement of the attachment longitudinally of the standard and said head, a treadle pivotally mounted in the base of said machine, means involving a yieldable coupling for placing 45 said plunger in operative engagement with the treadle whereby in the downward movement of said treadle, said attachment is fed downwardly through the action of said yieldable coupling, means in operative engagement with the treadle 50 for moving the attachment upwardly out of engagement with a workpiece when the downward pressure on said treadle is released, and said yieldable coupling involving adjustable means for regulating the relative position of the treadle 55 and said attachment.

14. A machine of the class described comprising a base, a tubular standard extending upwardly from the base, a tool operating head at the upper end of the standard, a tool operating attachment, a plunger mounted in said standard and having means therein and projecting therefrom for supporting and guiding the attachment in the movement of the attachment longitudinally of the standard and said head, a treadle pivotally mounted in the base of said machine, means involving a yieldable coupling for placing 65 said plunger in operative engagement with the treadle whereby in the downward movement of said treadle, said attachment is fed downwardly through the action of said yieldable coupling, means in operative engagement with the treadle 70 for moving the attachment upwardly out of engagement with a workpiece when the downward pressure on said treadle is released, and said yieldable coupling involving adjustable means for regulating the relative position of the treadle 75 and said attachment.

- for moving the attachment upwardly out of engagement with a workpiece when the downward pressure on said treadle is released, said yieldable coupling involving adjustable means for regulating the relative position of the treadle and said attachment, and adjustable means cooperating with said head for gaging the movement of said attachment in the direction of a workpiece.
15. A machine of the class described comprising a base, a tubular standard extending upwardly from the base, a tool operating head at the upper end of the standard, a tool operating attachment, a plunger mounted in said standard and having means therein and projecting therefrom for supporting and guiding the attachment in the movement of the attachment longitudinally of the standard and said head, a treadle pivotally mounted in the base of said machine, means involving a yieldable coupling for placing said plunger in operative engagement with the treadle whereby in the downward movement of said treadle, said attachment is fed downwardly through the action of said yieldable coupling, means in operative engagement with the treadle for moving the attachment upwardly out of engagement with a workpiece when the downward pressure on said treadle is released, said yieldable coupling involving adjustable means for regulating the relative position of the treadle and said attachment, adjustable means cooperating with said head for gaging the movement of said attachment in the direction of a workpiece, adjustable means for limiting the downward movement of said treadle, a yieldable buffer for checking the upward movement of said treadle when manual pressure thereon is released, a stripping device adjustably mounted upon said tubular standard, and a stripper plate adjustably supported in said device.
18. In a tapping machine employing a tool operating head with a quill slidably engaging said head, an adapter mounted on said quill, a tapping attachment detachable with respect to said adapter, a tubular support arranged longitudinally of and in spaced relation to said quill, and means independent of the quill and coupled with said adapter and mounted in and movable longitudinally of said support for supporting and guiding the attachment in the machine in its movement toward and from the workpiece in performing a tapping operation.
19. In a tapping machine employing a tool operating head with a quill slidably engaging said head, an adapter mounted on said quill, a tapping attachment detachable with respect to said adapter, a tubular support arranged longitudinally of and in spaced relation to said quill, means independent of the quill and coupled with said adapter and mounted in and movable longitudinally of said support for supporting and guiding the attachment in the machine in its movement toward and from the workpiece in performing a tapping operation, and means associated with said last named means for counterbalancing the attachment in the machine and for adjusting the normal position thereof with respect to said head and for providing a yieldable feed of the attachment in the direction of a workpiece supported in the machine.
20. In a tapping machine employing a tool operating head with a quill slidably engaging said head, an adapter mounted on said quill, a tapping attachment detachable with respect to said adapter, a tubular support arranged longitudinally of and in spaced relation to said quill, means independent of the quill and coupled with said adapter and mounted in and movable longitudinally of said support for supporting and guiding the attachment in the machine in its movement toward and from the workpiece in performing a tapping operation, and said means comprising a plunger having a pair of anti-frictional rollers at the upper and lower end portions thereof arranged and operating in said tubular support.
16. A machine of the class described comprising a base, a tubular standard extending upwardly from the base, a tool operating head at the upper end of the standard, a tool operating attachment, a plunger mounted in said standard and having means therein and projecting therefrom for supporting and guiding the attachment in the movement of the attachment longitudinally of the standard and said head, a treadle pivotally mounted in the base of said machine, means involving a yieldable coupling for placing said plunger in operative engagement with the treadle whereby in the downward movement of said treadle, said attachment is fed downwardly through the action of said yieldable coupling, means in operative engagement with the treadle for moving the attachment upwardly out of engagement with a workpiece when the downward pressure on said treadle is released, said yieldable coupling involving adjustable means for regulating the relative position of the treadle and said attachment, adjustable means cooperating with said head for gaging the movement of said attachment in the direction of a workpiece, adjustable means for limiting the downward movement of said treadle, a yieldable buffer for checking the upward movement of said treadle when manual pressure thereon is released, said yieldable coupling involving adjustable means for regulating the relative position of the treadle and said attachment, adjustable means cooperating with said head for gaging the movement of said attachment in the direction of a workpiece, adjustable means for limiting the downward movement of said treadle, and a yieldable buffer for checking the upward movement of said treadle when manual pressure thereon is released.
17. A machine of the class described comprising a base, a tubular standard extending upwardly from the base, a tool operating head at the upper end of the standard, a tool operating attachment, a plunger mounted in said standard and having means therein and projecting therefrom for supporting and guiding the attachment
